HYDRAULIC PUNCH AND STRIPPING
DEVICE

Otto Mueller, Dearborn, Mich.

Application August 11, 1947, Serial No. 767,963

17 Claims. (Cl. 164—95)

1

This invention relates to punching and stripping devices and particularly to a device for operating a pressure plate to hold the work during the advancing and withdrawing operations of the punch by hydraulic pressure.

In Patent No. 2,353,488, issued July 11, 1944, a device is illustrated having a moving cylinder for producing the punching and stripping operations when the cylinder is utilized as a slide and operated over a stationary piston.

The present device is structurally different from that of the patent and embodies a stationary or movable frame having a cylinder mounted on one end and a die-supporting standard on the other end in alignment with the cylinder. A slide operates on the frame and carries the punches and the pressure plate along with rods in engagement therewith. On the cylinder side of the slide, a piston rod is mounted having a piston which operates in the cylinder. A telescoping piston is mounted on the piston rod in the cylinder for engaging a plate which contacts the ends of the rods for applying a pressure to the pressure plate.

The two pistons may be moved in unison and may be actuated relative to each other. An aperture is provided in the main piston and rod into which a tubular element extends through which fluid is introduced into the main piston rod from which it is conducted between the two pistons. Fluid is first introduced into the piston rod and between the pistons for producing the advancement of the telescoping piston, the pressure plate rods and the pressure plate so that the front face of the latter extends beyond the forward ends of the punches. Fluid is then introduced into the main cylinder for moving the main piston, the rod, the telescoped piston, the slide, punches and pressure plate forwardly toward the work to be punched. Upon engagement with the work, resistance is offered to the movement by the fluid between the telescoped and main pistons, the pressure exerted thereby on the pressure plate and work being controlled by a pressure regulating valve which bleeds off the fluid between the pistons at a desired pressure as the main piston continues to advance to move the punch or punches through the work. Pressure is maintained on the workpiece by the pressure of the fluid between the telescoping and main pistons. After the punching operation, fluid is again directed between the telescoping and main pistons, while the fluid back of the main piston in the main cylinder is directed to tank. The

2

building up of pressure between the pistons causes the main piston to be retracted within the main cylinder, while the telescoping piston applies the pressure to the pressure plate for retaining the work in clamped position as the ends of the punches are withdrawn therefrom. After the withdrawing operation, fluid is then introduced into the forward end of the cylinder in engagement with the forward end of the telescoping piston for producing the retrograde movement of both of the pistons, the slide, punches and pressure plate to their initial positions, with the pressure plate still in advanced position ahead of the punch, ready for a subsequent operation.

Accordingly, the main objects of the invention are to provide a punching and stripping device having one piston telescoped on the piston rod of the main piston for applying pressure to the pressure plate as the punches are retracted when a fluid is admitted between the pistons; to provide a punching and stripping device embodying a fixed cylinder having a piston and piston rod extending therefrom, along with a telescoping piston and rod which operate relative to each other in unison on the wall of the fixed cylinder; to provide a punching and stripping device having a pair of telescoping pistons which may operate in unison or relative to each other for providing pressure on a pressure plate while the punch is advanced and retracted from the work; to construct punching and stripping devices of narrow width so that they may be nested about a wheel rim to punch closely adjacent holes therein; and, in general, to provide a punching and stripping device which is simple in construction, positive in operation and economical of manufacture.

Other objects and features of novelty of the invention will be specifically pointed out or will become apparent when referring, for a better understanding of the invention, to the following description taken in conjunction with the accompanying drawings, wherein:

Figure 1 is a sectional view of a punching and stripping device embodying features of this invention, with parts shown in position after a punching operation has been performed;

Fig. 2 is a sectional view of the structure illustrated in Fig. 1, taken on the line 2—2 thereof;

Fig. 3 is a broken view of the structure illustrated in Fig. 1, with the parts shown at the beginning or end of the punching and stripping operations;

Fig. 4 is a sectional view of the structure illus-

trated in Fig. 1, taken on the line 4—4 thereof;

Fig. 5 is a view of a machine for punching holes in the rim of a wheel, showing a further form of the invention;

Fig. 6 is an enlarged sectional view of the structure illustrated in Fig. 5, taken along the line 6—6 thereof, with the punch in retracted position, and

Fig. 7 is a sectional view of the structure illustrated in Fig. 6, taken along the line 7—7 thereof.

In Figs. 1 to 4, a base 11 is illustrated, having ways 12, a standard 13 at one end, and a collar 14 at the other for receiving and supporting a cylinder 15 thereon. The cylinder has an enlarged end 16 and is provided with a thread 17 on the opposite end on which a nut 18 is threaded for securing the cylinder to the collar. The standard 13 is provided with a work plate 19 containing one or more dies 21. Apertures 22 are provided in the plate 19 and standard 13, permitting the punched slugs passing through the dies 21 to be advanced in the apertures and finally ejected from the device.

The ways 12 support a slide 23 on the base 11, having a punch supporting plate 24 to which the punch holders 25 are secured for supporting the punches 26 aligned with the dies 21. A pressure plate 27 is provided with apertures through which the punches extend. The plate is mounted by means of a collar 28 secured over a sleeve 29 which is attached to the forward face of the plate 24 by a screw 31. A shoulder 32 on the sleeve 29 limits the outward movement of the collar 28 by the engagement of its shoulder 33 thereof. A plurality of rods 34 extend through the slide 23 and plate 24 in engagement with the pressure plate 27.

Rearwardly of the slide, a piston rod 35 is secured thereto by a screw 36. The opposite end of the rod is provided with a main piston 37 which operates on the internal wall of the cylinder 15. A piston 38 and piston rod 39 are telescoped over the main piston rod 45, with the piston 38 contacting the wall of the cylinder 15, while the rod 39 contacts the wall of the main piston rod 35. The forward end of the piston rod 38 is secured to a plate 41 which abuts the rear ends of the rods 34.

A cap 42 is secured to the left-hand end of the cylinder 15, as viewed in the figure, by a plurality of screws 43, the cap being sealed to the outer surface of the auxiliary piston rod 39 by suitable O-rings 44. Similarly, the inner surface of the auxiliary piston rod 39 is sealed to the surface of the main piston rod 35 by an O-ring 45. Metal sealing rings 46 seal the main piston 37 and the telescoping piston 38 to the inner wall of the main cylinder 15. An O-ring 47 may be employed between the cap 42 and the end of the cylinder 15 to form a seal therewith.

The main piston 37 and its associated rod 35 are provided with a cavity 48 and an aperture 49. The aperture 49 has its wall in engagement with the outer surface of a sleeve 51 having a passageway 52 therein which communicates with the cavity. A sealing ring 53 seals the surface of the sleeve 51 with the wall of the aperture 49. The head 54 of the cylinder has a central aperture 55 through which the end of the tubular element extends and is clamped in fixed relation thereto by a nut 56. A shoulder 57 on the interior of the cylinder is sealed to the inner face of the head 54 by a sealing ring 58. An annular groove 59 is provided about the sleeve 51 which is connected

by a passageway 61 to the passageway 52 within the element. A passageway 62 in the head conducts a fluid into the cavity 48 of the main piston rod 35. A passageway 63 is also provided in the head for conducting fluid to and from the cylinder 15. A passageway 64 is provided between the cavity 48 and an annular recess 65 provided in the inner wall of the encompassing piston 38. An annular passageway 66 is provided about the inner wall of the annular piston 38 having adjacent to the bottom thereof a passageway 67 through the wall of the annular piston 39. An annular slot 68 is provided about the main piston rod 35 of a width to span the bottom of the passageway 68 and the passageway 61.

With the device in the position illustrated in Fig. 3, a workpiece 69 is placed in the space between the work plate 19 and the pressure plate 27 and fluid is introduced into the passageway 63 to move the main piston 37 toward the workpiece. This advances the main piston rod 35, the slide 23, along with the punch supporting plate 24, elements 25 and punches 26. The telescoping piston 38 and rod 39 are maintained in fixed position ahead of the piston 37 on the main piston rod 35 to maintain the rods 34 and pressure plate 27 also in advanced position. The pressure plate forces the workpiece 69 against the work plate 19, and as the piston 37 continues to advance the slide 23, pressure will build up between the pistons 37 and 38 until a predetermined pressure is applied by the pressure plate 27 to the work 69. Thereafter, a pressure regulating valve in the fluid system (not illustrated) will open to hold the pressure between the two pistons constant as the piston 37 continues to advance the slide, the supporting plate 24 and punch holders 25 to move the punches through the apertures in the pressure plate 27 and thereafter to perform the punching operation on the workpiece 69.

After the completion of the power stroke by the main piston to perform the punching operation, the flow of fluid is reversed, that within the cylinder 15 being directed from the passageway 63 to tank. Fluid under pressure is admitted to the passageways 62 and 52, to the cavity 48 where it passes from the passageway 64 into the recesses 65 and 66. This fluid pressure applies a holding force to the pressure plate 27 and a force to the adjacent side of the piston 37, to thereby retract the piston 37 in the cylinder 15 and withdraw the punches from the work 69 into the aperture in the pressure plate 27. Thereafter, the passageway 66 is joined to the passageway 67 through the annular groove 68 in the main piston rod 35. This fluid is delivered to the space between the cylinder cap 42 and the telescoping piston 38 to an additional slight passageway 71 to move the two pistons while in separated position to the rearmost position in the cylinder 15 to have all of the elements of the device in the same position and relationship had at the beginning of the operation.

The device is believed to be novel in providing the main and telescoping pistons which operate in the same cylinder 15 relative to each other during the punching and stripping operations. The telescoping piston 38 is maintained in advancement of the piston 37 prior to the punching operation, and during the punching operation the fluid therebetween is by-passed to tank through a pressure regulating valve, to thereby maintain a predetermined pressure on the workpiece during the punching operation. The retraction of the punches to the position had prior

thereto is accomplished by the admission of fluid pressure between the pistons which provides a holding pressure for the piston 38 and pressure plate 27 and a retracting pressure for main piston 37 and the punches. After the two pistons 37 and 38 have assumed the initial separated relationship, the fluid then returns both pistons as a unit to their initial positions in the cylinder 15 ready for another punching operation.

It will be noted that both pistons are moved together and that only a small relative movement is provided therebetween so that only a minimum quantity of fluid is required for producing the holding and punching pressures.

While the cylinder 15 is illustrated as a separate element, it is to be understood that it could be part of the base casting. It is believed, however, that the sleeve arrangement is preferable because of leakage which may occur caused by porosity and blow holes in cast materials. It will be noted further from Fig. 3 that the fluid in the area 73 ahead of the encompassing piston 38 is free to pass to the other side of the piston and out through the passageway 62 through the pressure relief valve to tank during the initial rapid advancement of the slide. As soon as the pressure plate engages the work, the passageway 67 is cut off from the passageway 66, and the further advancement of the piston 37 relative to piston 38 causes the fluid therebetween to be forced past the pressure regulating valve into tank, thereby maintaining a set pressure on the workpiece during the punching operation.

The introduction of fluid between the two pistons produces a holding pressure for the work and the withdrawal of the punches therefrom as the piston 37 is moved away from the piston 38. Thereafter, the fluid being admitted between the two pistons is again free to pass ahead of the piston 38 and retract the two pistons, slide, pressure plate and punches to their initial positions. Therefore, a free passage of fluid to and from the area 73 is provided during the approach and return cycles which occur in a rapid manner.

It is further to be understood that while a single screw 31 is illustrated for holding the pressure plate 27 in position, that additional screws may be provided, located in different points of the plate depending on the position of the punches. If a central punch is being employed, then a pair of the holding elements embodying the sleeves 28 and 29 and screw 31 would be utilized.

In the device herein illustrated the power piston has an effective area of 7.85 square inches. The stripping piston has an effective area of 5.45 square inches and the return piston has an effective area of 1.91 square inches. The cylinder has a 3 1/4" bore, providing a device having substantial power for performing the punching and stripping operations and requiring only approximately 26 cubic inches of oil per cycle to operate.

Referring to Fig. 5, a further form of the invention is illustrated, that wherein a machine is provided embodying a bed 75 having four fixtures 76 mounted thereon spaced 90° apart. Each fixture is provided with three punching and stripping devices 77 so that four groups of three holes may be punched through the web of a wheel rim 78 in a single operation. The rim is dropped into a fixture (not illustrated) and the fluid is directed into the devices 77 simul-

taneously or seriatim to produce the punching operations. Each of the punches 77 is the same and this is shown in section in Figs. 6 and 7.

Referring to Figs. 6 and 7, the punching and stripping device 77 comprises a yoke 79 having the main body portion mounted on a slide 81 of the fixture 76. A block 82 extends through a slot 83 on the projecting end 84 of the yoke 79, having a screw 85 therein projecting in a thread of a lock block 86 and adjustable in a T-slot 87. A rod 88 extends forwardly from the block 82 about which a spring 89 is disposed in a slot 91 in the base of the yoke 79. The spring urges the yoke 79 toward the center of the rim 78 until the rear face of the slot 83 strikes the block 82.

In the forward end the yoke 79 has a projecting end 92 carrying the punch die 93. The opposite end of the yoke 79 carries a boss 94 having a sleeve 95 machined thereon for receiving the cylinder 96 of the punching and stripping device. The cylinder 96 has a slot 97 medially of its ends in which a split ring 98 may be disposed. The cylinder 96 is disposed in the sleeve 95 from the forward side, after which the two halves of the ring 98 are applied to the slot 97 and move into the shoulder 99 in the forward end of the cylinder 95. Thereafter, a clamping ring 101 is screwed upon the rear end of the cylinder to clamp the cylinder 96 within the sleeve 95. Thereafter, the stripping piston 102 is inserted within the cylinder 96, being sealed thereto by a plurality of piston rings 103. Forwardly of the cylinder a hollow piston rod 104 is provided, having splines 105 thereon mating with the areas between splines 106 within the forward end 107 of the cylinder 96. The forward end of the cylinder is sealed to the sleeve 104 by an O-ring 108 disposed within the slot provided on the inward wall thereof. The splines 105 and 106 prevent the rotation of the sleeve 104 with the cylinder 96 in order to align the punch with the die 93 if a hole other than circular is to be punched. Otherwise the splines may be omitted from the device.

A punch operating piston 109 is then inserted within the cylinder 96, the piston having a piston rod 111 extending forwardly thereof. The piston rod is solid the greater part of its length and carries on the end thereof a punch 112 secured in position by a clamping collar 113. The inner wall of the sleeve 104 at the forward end is provided with keyways 114 in which keys 115 in the piston rod 111 operate to prevent the piston rod 111 from turning relative to the sleeve 104. Similarly, the punch 112 is provided with one or more flat faces 116 which position the punch relative to the piston rod 111.

The piston 102 is hollow to permit the piston rod 111 to project therethrough, and the piston 109 is also provided with a central opening 117 through which a conduit 118 passes into a recess 119 in the rear end of the piston rod 111. The conduit 118 is supported by the end cap 121 which is threaded or otherwise secured to the end of the cylinder 96 and sealed thereto by an O-ring 122. The conduit 118 has a boss 123 which extends through the end cap to be secured in position thereon by a washer 124 and nut 125 and sealed thereto by O-rings 126. The passageway 127 in the conduit 118 communicates through an aperture 128 in the cap 121, with a supply conduit (not shown) connected thereto through a threaded port 129. The cap also is provided with a passageway 131 extending from a threaded port 132 to the interior of the cap to communicate

with fluid at the rear end of the punch piston 109. The fluid introduced into the passageway 127 passes into the recess 119 of the piston rod 111 from which it is directed between the pistons 102 and 109 through an aperture 138.

An annular passageway 134 is provided between the piston rod 111 and the piston 102. A similar annular passageway 135, in the nature of a recess, is provided in the wall of the piston rod 111. The sleeve 104 is provided with a passageway 136 for the passage of a fluid to and from the area ahead of the pressure plate piston 102. The sleeve 104 has a pressure applying plate 137 in the nature of a cap which is threaded to the end of the sleeve and provided with a central aperture 138 through which the punch 112 may be relatively advanced and retracted. In the position illustrated in Fig. 6, the punch is in retracted position, with the piston 102 advanced forwardly from the piston 109 to have the pressure plate 137 extend forwardly of the end of the punch. This provides a space between the pressure plate and the die 93 which permits the machine to be loaded with the rim 78 and the dished hub portion 139.

Fluid is introduced through the passageway 131 to the rear of the piston 109 to advance the pistons 109 and 102 simultaneously toward the die 93. Fluid between the pistons is prevented from passing out of the passageway 128 and port 129 by a pressure relief valve (not illustrated) in the conduit connected to the port 129. When the pressure plate 137 strikes the rim 78, the reaction thereto causes the yoke 79 to be moved to the left, as viewed in the figure, to advance the die 93 into engagement with the disk 139 so that the disk and rim are clamped between the die 93 and pressure plate 137. The further application of fluid in the rear of the piston 109 causes the piston to advance and the fluid between the piston 109 and 102 to be forced out through the port 129, past the pressure relief valve, so that the plate 137 will always maintain engagement with the workpiece and die 93 at the predetermined set pressure of the relief valve.

This differential movement between the pistons 102 and 109 causes the die 112 to advance through the workpieces and to perform the desired punching operation thereon. The relationship of the two pistons at the end of the punching operation is illustrated in Fig. 7. It will be noted that the pressure plate is still exerting pressure on the workpieces against the die 93 and that the die is advanced to completed punching position. The flow of fluids is then reversed in the ports 132 and 129 so that fluid is introduced into the port 129 and conducted to tank from port 132, as viewed in Fig. 7. The fluid passing into the passageways 129 and 127 into the recess 119, through the passageway 138 into the annular passageway 134, causes the piston 109 to be moved to the left relative to the piston 102. This retracts the punch 112 with relation to the pressure plate 137 to a position as illustrated in Fig. 6. In this position fluid may pass to the recess 135 and the wall of the piston rod 111, through the passageway 136 ahead of the piston 102 to cause the piston to be moved to the left, carrying the piston 109 along therewith spaced from the piston 102. This relationship maintains until the piston 109 reaches the end of the cylinder 96 and all parts are in the position as shown in Fig. 6 which is the position had at the beginning or end of the punching operation.

It will be noted that the pressure employed for withdrawing the punch from the workpieces

after the punching operation is applying at the same time an equal amount of pressure forwardly on the pressure plate 137 to hold the workpieces in position against the punch 93 during the withdrawal of the punch therefrom. The rearward movement of the piston 109 relative to the piston 102 is prevented beyond the amount to retract the punch 112 by the cap 113 which holds the punch 112 on the end of the piston rod 111 engaging a shoulder 141 on the inner wall of the sleeve 104. This occurs after a passageway has been completed from the recess 134 to the recess 135 in the inner wall of the piston 102 and the outer wall of the piston rod 111, respectively. After the pressure plate 137 is retracted from the workpieces, the spring 89 moves the yoke 79 to the right, thereby moving the die 93 away from the workpiece so that it may be removed and a new set of elements to be punched inserted in the machine. It will be noted that the forward end 92 of the yoke 79 is tapered so that the three devices grouped together to produce three punch holes at the 90° points on the wheel may be nested close together so that closely spaced holes may be punched by the devices. While the punching device only is claimed in the present application, the arrangement of the plurality of devices for punching apertures in a wheel rim is claimed in the copending application, Serial No. 226,431, filed May 15, 1951.

What is claimed is:

1. In a device for performing a punching and stripping operation, a punch carrying piston and piston rod, a stripper carrying piston and rod telescoped over said first rod, with the pistons having the same diameter, a cylinder in which the pistons operate in unison and relative to each other, said device incorporating means for conducting a fluid to the working end of the punch carrying piston, means for conducting a fluid between the pistons, and means for conducting a fluid from between the pistons to the retracting end of the stripper carrying piston after the pistons have been separated a predetermined amount to thereafter move both pistons simultaneously within the cylinder while maintained in separated relation.

2. In a device for performing a punching and stripping operation, a punch carrying piston and piston rod, a stripper carrying piston and rod telescoped over said first rod, with the pistons having the same diameter, a cylinder in which the pistons operate in unison and relative to each other, a slide carried by the punch carrying piston rod, a pressure plate mounted ahead of said slide, means operatively connecting the pressure plate to said telescoping piston rod, said device incorporating means for conducting a fluid to the working end of the punch carrying piston, means for conducting a fluid between the pistons, and means for conducting a fluid from between the pistons to the retracting end of the stripper carrying piston after the pistons have been separated a predetermined amount to thereafter move both pistons simultaneously within the cylinder while maintained in separated relation.

3. In a device for performing a punching and stripping operation, a punch carrying piston and piston rod, a stripper carrying piston and rod telescoped over said first rod, with the pistons having the same diameter, a cylinder in which the pistons operate in unison and relative to each other, a slide carried by the punch carrying piston rod, a pressure plate mounted ahead of said slide, means operatively connecting the pressure

plate to said telescoping piston rod, a base on which said slide operates, means on one end of the base for supporting the cylinder, means on the opposite end of the base, for supporting a work plate, punches carried by said slide projecting through apertures in said pressure plate, dies carried by said work plate in alignment with said punches, said device incorporating means for conducting a fluid to the working end of the punch carrying piston, means for conducting a fluid between the pistons, and means for conducting a fluid from between the pistons to the retracting end of the stripper carrying piston after the pistons have been separated a predetermined amount to thereafter move both pistons simultaneously within the cylinder while maintained in separated relation.

4. In a device for punching and stripping a workpiece comprising a cylinder, a pair of pistons in engagement with the wall of the cylinder and having rods disposed in telescoped relation to each other, a slide operated by one of said rods, a punch on said slide, a pressure plate operated by the other of said rods, and means for trapping fluid under pressure between said pistons for applying a holding force to the pressure plate by one of said pistons to retain it in advance of said punch when the other piston is initially moved to advance both pistons together.

5. In a device for performing a punching and stripping operation comprising a cylinder, a pair of pistons and rods disposed in telescoped relation in the cylinder, a slide secured to one rod, a punch on said slide, a pressure plate carried by said slide having an aperture through which said punch may extend and having connection with said other rod, said cylinder and rods having fluid passageways for fluid for producing relative movement between the pair of pistons in the cylinder for advancing the pressure plate ahead of the slide and punch for producing movement of the spaced pistons as a unit when the slide piston has fluid applied thereto for advancing the pressure plate into engagement with the work for maintaining pressure on the other piston and pressure plate as the slide is further advanced to perform the punching operation and for producing a relative movement between the two pistons for holding the pressure plate in position as the punch and slide are retracted and for moving both pistons when in spaced relation as a unit to return all parts to initial position.

6. In a device for performing a punching and stripping operation on a workpiece comprising a base, a cylinder on one end of the base, a standard on the opposite end of the base, a slide mounted on the base for movement between said cylinder and standard, a piston within the cylinder having a rod connected to said slide, a second piston within the cylinder having a rod, said second piston and cylinder telescoping over said first rod, a pressure plate carried by said slide in advance thereof for reciprocal movement relative thereto, and means connecting the pressure plate to said telescoping piston rod to produce a movement thereof relative to said slide conforming to the movement of said last rod.

7. In a device for performing a punching and stripping operation on a workpiece comprising a base, a cylinder on one end of the base, a standard on the opposite end of the base, a slide mounted on the base for movement between said cylinder and standard, a piston within the cylinder having a rod connected to said slide, a second piston within the cylinder having a rod,

said second piston and cylinder telescoping over said first rod, a pressure plate carried by said slide in advance thereof for reciprocal movement relative thereto, means connecting the pressure plate to said telescoping piston rod to produce a movement thereof relative to said slide, and means for introducing fluid to said first piston for advancing the slide, second piston and pressure plate as a unit with said second piston disposed in advance of said first piston.

8. In a device for performing a punching and stripping operation on a workpiece comprising a base, a cylinder on one end of the base, a standard on the opposite end of the base, a slide mounted on the base for movement between said cylinder and standard, a piston within the cylinder having a rod connected to said slide, a second piston within the cylinder having a rod, said second piston and cylinder telescoping over said first rod, a pressure plate carried in advance of said slide, means connecting the pressure plate to said telescoping piston rod to produce a movement thereof relative to said slide, means for introducing fluid to said first piston for advancing the slide, second piston and pressure plate as a unit, and means for trapping fluid between said two pistons for maintaining said second piston in advance of the first piston during the advancement of both pistons.

9. In a device for performing a punching and stripping operation on a workpiece comprising a base, a cylinder on one end of the base, a standard on the opposite end of the base, a slide mounted on the base for movement between said cylinder and standard, a piston within the cylinder having a rod connected to said slide, a second piston within the cylinder having a rod, said second piston and cylinder telescoping over said first rod, a pressure plate carried in advance of said slide, means connecting the pressure plate to said telescoping piston rod to produce a movement thereof relative to said slide, means for introducing fluid to said first piston for advancing the slide, second piston and pressure plate as a unit, means for conducting fluid to an area between said two pistons for producing relative movement therebetween, and additional means for directing fluid from between said piston to a point ahead of said telescoping piston for producing the retraction of the pistons in separated relation within the cylinder after performing the punching and stripping operations.

10. In a device for performing a punching and stripping operation in a workpiece, a base, a cylinder on said base, a slide on said base, a piston in said cylinder, a piston rod connecting said piston to said slide, a telescoping piston mounted on said piston rod, said device incorporating means for conducting a fluid to the working end of the one piston, means for conducting a fluid between the pistons, and means for conducting a fluid from between the pistons to the retracting end of the other piston after the pistons have been separated a predetermined amount to thereafter move both pistons simultaneously within the cylinder while maintained in separated relation.

11. In a device for performing a punching and stripping operation in a workpiece, a base, a cylinder on said base, a slide on said base, a piston in said cylinder, a piston rod connecting said piston to said slide, and a telescoping piston mounted on said piston rod, said telescoping piston being disposed within said cylinder in position to operate with and independently of said

11

first cylinder, means for preventing relative rotation between said second piston and cylinder, and means for preventing relative rotation between said first piston and said second piston.

12. In a device for performing a punching and stripping operation in a workpiece, a base, a cylinder on said base, a slide on said base, a piston in said cylinder, a piston rod connecting said piston to said slide, a telescoping piston mounted on said piston rod, said telescoping piston being disposed within said cylinder in position to operate with and independently of said first cylinder, a sleeve within said cylinder over which said first piston operates having a passageway communicating with the outside of the cylinder for directing fluid to an area between said two pistons, said telescoping piston having passageways which conduct fluid to the slide side of said telescoping piston for retracting both pistons when separated a predetermined distance by fluid conducted therebetween, and a piston stop for regulating the degree of separation of said pistons.

13. In a device for performing a punching and stripping operation in a workpiece, a base, a cylinder on said base, a slide on said base, a piston in said cylinder, a piston rod connecting said piston to said slide, a telescoping piston mounted on said piston rod, said telescoping piston being disposed within said cylinder in position to operate with and independently of said first cylinder, a sleeve within said cylinder over which said first piston operates having a passageway communicating with the outside of the cylinder for directing fluid to an area between said two pistons, and means operative when said pistons are moved to separated position for connecting the area between said pistons to a passageway ahead of the telescoping piston for moving both pistons as a unit within the cylinder.

14. In a device for performing a punching and stripping operation, a main piston and piston rod, a second piston and rod telescoped over said first rod, said pistons having the same diameter, a cylinder in which said pistons operate in unison and relative to each other, a punch carried by said main piston rod, a pressure plate carried by said telescoping piston rod and encompassing said punch when the latter is retracted, a base on which said device is slidable, and means for urging said device to one position on said base, said device incorporating means for conducting a fluid to the working end of one piston, means for conducting a fluid between the pistons, and means for conducting fluid from between the pistons to the retracting end of the other piston after the pistons have been separated a predetermined amount to thereafter move both pistons simultaneously within the cylinder while maintained in separated relation, said device being moved from said one position by the action of said one piston when the punch is advanced to perform the punching operation.

15. In a device for performing a punching and stripping operation, a C-shaped frame, a cylinder carried by one end of said frame, a die carried by the other end of said frame, a piston in said cylinder, a rod extending from said cylinder aligned with said die, a second piston and rod in said cylinder telescoped over said first rod and

operable in said cylinder with and independently of said first piston, a punch carried by said first rod, a pressure element carried by said telescoping rod through which said punch operates, a slide on which said C frame is supported, said device incorporating means for conducting a fluid to the working end of the one piston, means for conducting a fluid between the pistons, and means for conducting a fluid from between the pistons to the retracting end of the other piston after the pistons have been separated a predetermined amount to thereafter move both pistons simultaneously within the cylinder while maintained in separated relation.

16. In a device for performing a punching and stripping operation, a C-shaped frame, a cylinder carried by one end of said frame, a die carried by the other end of said frame, a piston in said cylinder, a rod extending from said cylinder aligned with said die, a second piston and rod in said cylinder telescoped over said first rod and operable in said cylinder with and independently of said first piston, a punch carried by said first rod, a pressure element carried by said telescoping rod through which said punch operates, a slide on which said C frame is supported, means for moving said frame on said slide, said device incorporating means for conducting a fluid to the working end of the one piston, means for conducting a fluid between the pistons, and means for conducting a fluid from between the pistons to the retracting end of the other piston after the pistons have been separated a predetermined amount to thereafter move both pistons simultaneously within the cylinder while maintained in separated relation.

17. In a device for performing a punching and stripping operation, a C-shaped frame, a cylinder carried by one end of said frame, a die carried by the other end of said frame, a piston in said cylinder, a rod extending from said cylinder aligned with said die, a second piston and rod in said cylinder telescoped over said first rod and operable in said cylinder with and independently of said first piston, a punch carried by said first rod, a pressure element carried by said telescoping rod through which said punch operates, a slide on which said C frame is supported, a spring urging said frame toward one end of said slide, said device incorporating means for conducting a fluid to the working end of the one piston, means for conducting a fluid between the pistons, and means for conducting a fluid from between the pistons to the retracting end of the other piston after the pistons have been separated a predetermined amount to thereafter move both pistons simultaneously within the cylinder while maintained in separated relation.
